[57] **CLAIM**

The ornamental design for a storage box, as shown and described.

DESCRIPTION

FIG. 1 is a front perspective view of a storage box showing my new design;
FIG. 2 is a side perspective view thereof;
FIG. 3 is a top plan view thereof;
FIG. 4 is a side elevational view thereof, the opposite side identical;
FIG. 5 is a front elevational view thereof, the rear being identical; and,
FIG. 6 is a bottom plan view of the top member of the storage box shown separately for ease of illustration.
